TARGET CARRYING AND TARGET TURNING
DEVICE

James L. Murphy, Jr., Washington, D.C.

Application July 31, 1947, Serial No. 764,986

10 Claims. (Cl. 273—105.6)

1

This invention relates to improvements in target apparatus for rifle or pistol ranges, armories and shooting galleries where small arms are used for firing at targets.

The invention relates more particularly to apparatus for simultaneously regulating the positions of the targets at the target station, and for causing the targets to move from the firing station to the target station.

In the past target carriers have been constructed so that the target may be moved from the firing station to the target station but no means has been provided for moving one or more of the targets from a non-firing position to a firing position at the target station for only a predetermined time. Heretofore the carriers to which the targets are secured were moved at the discretion of the shooter from the firing station to the target station, the targets having their full face facing the shooter throughout the movement. Such an arrangement does not provide a concealed target for most of the above stated operation and a firing position for only a predetermined time. Heretofore in shooting matches where a limited amount of time is allowed for a certain number of shots, it was difficult to insure that competitors did not fire early or late on the target which is in full view.

In the present construction provision is made for simultaneously turning one, or preferably a plurality of targets at the target station from an edgewise position to a firing position for a limited and predetermined amount of time. The targets may be in their exposed position but preferably are in their edgewise position throughout the travel to the target station and are rotated to present their full face position to the shooter only during the firing period, thus eliminating early and late shots (which cause confusion and argument). After the firing period, the targets are again turned to their edgewise position and may be moved by the shooter back to the firing station for purposes of examination of the targets. This latter movement gives the shooter or team an opportunity to attach new targets to the carrier in addition to determining the score of the previous round of shots.

The principal object of this invention is to provide a target conveying and turning device for use in rifle and pistol matches and for practice purposes, provided with mechanism whereby one or preferably a plurality of targets are turned from an edgewise position to a position for firing, for a limited period of time, after which the targets are again turned in edgewise position, thus allowing a definite time for firing of a given number of shots at the targets.

A further object of the invention is to provide target apparatus for use in rifle and pistol ranges wherein means is provided for causing the tar-

2

gets to move from the firing station to the target station in an edgewise position, wherein the targets may be turned to a full face position for a predetermined amount of time, wherein at the end of this time period the targets may be turned to their edgewise position and conveyed back to the firing station.

A still further object of the invention is to provide target apparatus for use in rifle and pistol ranges wherein means is provided to cause the targets to move from the firing station to the target station in an edgewise position, wherein the targets are turned for a limited amount of time to a full face position and then once again to their edgewise position, wherein all of these operations are accomplished by the shooter by means of manual controls at the firing station, although automatic turning means for the targets is not excluded.

Other objects, features and advantages of this invention will appear or be pointed out as the specification proceeds.

In the accompanying drawings forming part hereof:

25 Figure 1 is a top plan view of the target apparatus.

Figure 2 is a side elevation of the target apparatus which is also shown in Figure 1.

30 Figure 3 is a front elevation of the target and the target supporting means when located in shooting position.

Figure 4 is a side elevation of the target and target supporting means shown in Figure 3.

35 Figure 5 is a top plan view of a detail of the target oscillating device; and

Figure 6 is a vertical sectional view of the portion of the oscillating device shown in Figure 5.

Referring to the drawings, numeral 1 indicates the firing station which includes suitable base members 2, a plurality of upright members 3. On top of these upright members there is attached a beam 4 which extends completely across the top of the apparatus. The upright members 3 provide a frame member which supports a pulley 6, which is manually operated, and a pulley 10. The pulley 6 is mounted on the framework 3 by means of a shaft 5 and has a handle 7 which is operated by the shooter. As many of these pulleys may be provided as there are shooters.

50 The pulley 6 is provided with a V-groove for a belt 9 which extends over the pulley 6 and over the pulleys 10 and 11. The horizontal reaches of this rope numbered 13 also extend from pulleys 10 and 11 over two pulleys 14 and 15 which are located at the target station. The lower reach 13 of the belt or rope extends to the trolley member 16 where it is rigidly attached. The forward end 17 of this trolley member 16 is provided with an eye 18 for the reception of the end of the belt or rope 13. Attached to this trolley frame are two

brackets 20 upon which are rigidly mounted, by means of bolts 21, two trolley wheels 22. These trolley wheels 22 run over a wire rope 23 which is rigidly attached on the upright 3 of the firing line by means of an eye 24. The trolley wheels are prevented from moving past the target station by means of a bracket 25, which is secured to the framework 19. The bracket has a socket 26, the wire 23 passing through and being attached in the socket member 26, as shown in Figure 4.

Projecting downwardly from the trolley member 16 is a multi-sided supporting member 28 which is attached, as by welding, at its upper extremity to the trolley member 16. To the supporting member 28 is attached, as by welding, a bearing 27 which supports the target actuating part 30 having a projecting stud 31 attached thereto by means of a coupling member 32 adjustably slidable on the part 30. A screw may be provided to lock the sleeve in adjusted position on the rod 30, similar to that shown for locking the sleeves 69. Connected to this stud is the oscillating mechanism which will be hereinafter described.

The target actuating part 39 has a shield 33 which extends in front of the member 30 and serves to protect the member 30 and coupling 32 in either of the positions of these parts, from stray bullets. The member 30 has a right angled extension forming a shaft 29 adapted to rotate in the bearing 21. The shaft 29 is connected by coupling 34 to cylindrical extension 35 provided with a flattened end 36. This end has an aperture, not shown, through which a bolt 37 extends on which a wing nut 38 is mounted to thereby rigidly support, by means of the spring actuated clamping member 39, the target 40.

When the target has been moved to the position indicated in Figures 2, 3 and 4, the extension 35 is received in a stationary bearing or steadyng member 41. This member is of substantially V-shape, as seen in Figure 1, and is supported by a block 42. The parts 21, 42 are supported in a framework similar to that disclosed at the firing station, which consists of a base member 43, uprights 44, and a beam member 45. The bracket 25 may be supported by the usual bullet stop 100.

Mounted adjacent to the firing station and contiguous to the manually operated pulley 6 is a hand lever 45 which is pivoted, as shown in Figure 2, at 46, this latter attachment being secured to the supporting member 47. The lever 45 is provided with a handle 48 which is used to actuate the oscillating mechanism which is to be hereinafter described from an "on" to an "off" position to thereby cause the target to be rotated from a non-firing to a firing position and vice versa. The end opposite the handle is provided with a pivoted end 49 connected to a link 50, this latter link being pivotally connected at 51 to the flattened portion of a push arm or rod 52. The rod 52 passes through and slides in a bearing member 53 which is suitably attached to a supporting frame 54. The rod 52 extends from in front of the firing station to a bearing 55 which is likewise attached to a supporting frame 56. The rod or arm 52 similarly slides through bearing 55 and terminates in a flattened portion 57. This flattened portion is provided with an aperture 58 to which is pivotally connected a link 59 which in turn is pivotally connected at 60 to the flattened end of a shaft 61. Rigidly supported by the base member 43 is a bearing

62 which supports the shaft 61 at one end thereof. The other end of this bearing serves as a connection for a shaft 63, the link 61 and 63 forming a bell crank. The link 63 has a flattened portion 64 to which is pivotally connected through the pivot 65, the link 66, which is pivotally connected through a pivot 67 to the target actuating rod 68.

10 By referring to Figures 1, 5 and 6, the operation of the oscillating mechanism which turns the target from an edgewise to a full face position will be described. It should be understood that each target has a separate oscillating mechanism, each of these oscillating mechanisms, 15 however, being operated by sliding the actuating rod 68. Rigidly attached to the actuating rod 68 at spaced intervals are blocks 69 each of which has an extension 70 and a fork-like end portion 71. When the lever 45 is moved from one extremity to another the link members change 20 their position to the dotted lines as shown in Figure 1 and the fork-like portion 72 engages the pin 31 and rotates shaft 27 to cause target 40 to move through substantially a 90° angle, that is 25 from an edgewise position to a position facing the shooter.

The operation of the invention will be reviewed briefly:

Referring to Figures 1 and 2 the cycle of the operation starts when the pulleys 6 are manually rotated. The trolley wheels which carry the targets are then moved from the firing station to the target station. The shooters are now prepared to fire. When the lever 45 is operated by the target operator the targets which were previously in an edgewise position are now turned to a full face position by means of the movement of the rod 52 which in turn operates the actuating part 30 of each target. After a predetermined time the operator returns lever 45 to its initial position whereby the targets are again turned to their edgewise position. Each shooter by rotating the pulley 6 in the opposite direction causes his target to be carried back to the firing line, at which time the shooter may examine the results of his marksmanship. At this time it is possible to substitute a new target and again commence the cycle of operation.

Under some conditions it may be desired to use one or more non-rotating types of target carriers, while rotating targets are used by some of the shooters. This may be effected by removing shaft 28 from trolley member 16 and substituting a shaft similar to shaft 35, which may be either round or multi-sided in cross section. The lower end of the shaft would preferably be provided with a target supporting means such as indicated at 29, 36, 37 and 38.

It is to be expressly understood that suitable mechanism, such as a drum driven by a synchronous motor may be substituted for the hand lever 45, to thereby cause the automatic rotation of the targets from edgewise to exposed position and back to edgewise position.

1 65 The preferred embodiments having been fully
2 described in my invention, what I claim is new
3 and desire to secure by Letters Patent is:

1. In a target apparatus, the combination of
a firing station, a target station, a carrier hav-
ing a target secured thereto, means for trans-
porting said target from one station to the other,
said carrier including a shaft mounting said tar-
get, means for rotating said shaft including a
lever, and a forked member connected to said le-
ver.

2. In a target apparatus, the combination of a firing station, a target station, a carrier having a target secured thereto, means for transporting said target from one station to the other, said carrier including a shaft mounting said target, means for rotating said shaft including a lever, and a forked member connected to said lever, said carrier also including a pin adapted to be engaged by the said forked member when said carrier has reached said target station.

3. In a target apparatus, the combination of a firing station, a target station, a plurality of target carriers, individually operated means for causing movement of said target carriers from the target station to the firing station, and means for simultaneously rotating all of said targets from an edgewise position to a firing position and vice versa, said means for rotating all the said targets including a member on said target carrier and a shiftable rod manually operated by lever means at said firing station, said lever means being located along the side of the target apparatus whereby the line of fire between said stations is free of obstructions.

4. In a target apparatus, the combination of a firing station, a target station, a plurality of target carriers, individually operated means for causing movement of said target carriers from the target station to the firing station, and means for simultaneously rotating all of said targets from an edgewise position to a firing position and vice versa, said means for rotating said targets including a manually operated lever, a target actuating part on each of said carriers and a rod engageable with said part operated by said lever.

5. In a target apparatus, the combination of a firing station, a target station, a plurality of target carriers, individually operated means for causing movement of said target carriers from the target station to the firing station, and means for simultaneously rotating all of said targets from an edgewise position to a firing position and vice versa, said means for rotating said targets including a manually operated lever, a rod operated by said lever, and a target actuating part on each of said carriers, means including said rod for rotating said part through an angle of substantially 90 degrees to thereby rotate said target from an edgewise position to a target firing position.

6. In a target apparatus, the combination of a firing station, a target station, a plurality of target carriers each having a target secured thereto, individually operated means for causing movement of said target carriers from the target station to the firing station, said targets being moved between stations in their edgewise position, and manually operated lever means for simultaneously rotating all of said targets from an edgewise position to a firing position and vice versa, said target carriers each having a bearing, a shaft rotatable in said bearing, and means including members cooperating with said lever means for rotating said shaft.

7. In a target apparatus, the combination of a firing station, a target station, a plurality of target carriers, individually operated means for each carrier including a pulley and a flexible member mounted on said pulley for causing movement of said target carriers from the target station to the firing station, said pulley being located adjacent said firing station and manually operated lever means for simultaneously rotat-

ing all of said targets from an edgewise position to a firing position and vice versa, said target carriers each having a bearing, a shaft rotatable in said bearing, and means including members cooperating with said lever means for rotating said shaft, and a shield mounted in front of the cooperating members.

8. In a target apparatus, the combination of a firing station, a target station, a plurality of target carriers, individually operated means for causing movement of said target carriers from the target station to the firing station, and means including a manually operated lever for simultaneously rotating all of said targets from an edgewise position to a firing position and vice versa, said target carriers each having a bearing, a shaft rotatable in said bearing, and means including cooperating members for rotating said shaft, said cooperating members including a target actuating part rigidly connected to said rotating shaft and a rod engageable with said part and connected to said lever.

9. In a target apparatus, the combination of a firing station, a target station, a plurality of target carriers, individually operated means for causing movement of said target carriers from the target station to the firing station, and means including a manually operated lever for simultaneously rotating all of said targets from an edgewise position to a firing position and vice versa, said target carriers each having a bearing, a shaft rotatable in said bearing, and means including cooperating members for rotating said shaft, said cooperating members including a target actuating part rigidly connected to said rotating shaft, a pin extending vertically from said part, and a forked member connected to said lever adapted when actuated to engage said pin and rotate said target actuating part and shaft through an angle of substantially 90 degrees.

10. In a target apparatus, the combination of a firing station, a target station, a plurality of target carriers each of which has a target actuating part, individually operated means for causing movement of said target carriers from the target station to the firing station, and means including a manually operated lever for simultaneously rotating all of said targets from an edgewise position to a firing position and vice versa, a rod operated by said lever, said last-named means also including members connecting said lever and rod with each actuating part.
